INTERNAL COMBUSTION ENGINE

Victor F. Zahodiakin, Cincinnati, Ohio

Application June 8, 1933, Serial No. 674,892

10 Claims. (Cl. 123—188)

This invention relates to internal combustion engines and is particularly related to improvements in the structure of the valves for the engine, having particular application to the general type of valve disclosed in my Patent No. 1,950,911, July 28, 1932.

These valves are arranged to operate coaxially one within the other. In a more detailed sense, the inlet valve operates relative to a fixed seat within the exhaust valve and the exhaust valve operates relative to a seat disposed about the top of the combustion chamber. The exhaust valve, as will be apparent, is cylindrical or of the sleeve type and for purposes of stability and protection 15 operates within cylindrical guideways, the outside one of these guides extending substantially to the head of the valve. The heat generated by the explosion in the chamber and the expelled hot gases from the chamber in the exhaust stroke of 20 the piston create intense heat at the region of the exhaust valve head. All of the parts of the motor at this point are in an environment of constant operating heat tending to damage and destroy the metal over a period of time.

25 Due to the fact that the protective guideway is extended about the exhaust valve substantially to its head and across the exhaust passageway, it occurs that the hot gases passing between the exhaust valve head and its seat, the head being 30 of flared structure, have heretofore been directed against this guideway, resulting in undue burning of the metal and excessive heat, deforming the parts and weakening the tensile strength thereof.

Accordingly, it is the object of this invention 35 to provide an improved exhaust valve, particularly exhaust valve head, which, by the provision of a deflective formation in the flared head thereof, directs the exhaust gases as they pass by the seat and head away from the protective 40 sleeve or guideway, thus reducing materially the ravages of heat and the products of combustion on this guideway element, and at the same time directing the heat away from the sliding portion 45 or stem of the exhaust valve adjacent the head.

Other objects and further advantages will be more fully apparent from a description of the accompanying drawing, in which:

Figure 1 is a fragmentary sectional view taken 50 through the cylinder and exhaust passageway of an internal combustion engine, illustrating the exhaust valve in closed position and showing the improved valve head therefor.

Figure 2 is a sectional view taken similar to Figure 1, but showing the exhaust valve in open po-

sition for illustrating the function of the improved head structure in the deflection of hot gases.

In view of the fact that the present improvements are solely in connection with the exhaust valve and relate to the function of this valve for deflecting the hot gases from the guideway and the slideable portion or stem of the valve, the illustration is confined to the locality of one of the valve assemblies of the motor, the valve in head 10 type being selected for the purpose of disclosing the present improvements.

The engine type is generally indicated at 5 and is inclusive of a cylinder block 6 and cylinder head 7. The cylinder bore is indicated at 8 and the combustion chamber portion in the head at 9, there being no showing of the piston since its relation is well understood. The combustion chamber includes an exhaust port 10, coaxially extended from the cylinder and the combustion chamber and entering into or communicating 20 with a laterally extended exhaust passageway 11. The exhaust valve seat 12 is also concentric or coaxial being about the interior of the combustion chamber or marginally of the outlet thereof. The valve assembly is entered through the head 25 coaxially of the cylinder and is of the following construction.

A fixed guide 13 is mounted on the head and includes a depending cylindrical portion 14 extending within the exhaust passageway and terminating to provide an inlet valve seat 15 just above the plane of the exhaust valve seat. An inlet valve mounting in the form of a spider supported 30 tubular portion 16 is axially arranged in the cylindrical guideway and a removable guide 17 of sleeve form is mounted in this valve mounting or 35 valve support.

The inlet valve 18 is slidably mounted in the guide 17 and has its head 19 engaging the horizontally disposed lower end of the fixed guide, the incoming charge of gas being introduced 40 through the hollow cylinder and past the inlet valve when unseated.

The exhaust valve 20 is of cylindrical form 45 generally with a flared head 21 and is telescopically mounted over the cylindrical portion 14. An external guide of sleeve form 22 is mounted about the exhaust valve and extends across the exhaust 50 passageway terminating slightly above the exhaust outlet opening or a point substantially in the same plane as the lower end of the inlet valve seat 15. This guide extends downwardly as far as feasible, that is to say, insofar as it will not interfere with the seating of the exhaust valve. 55

The flared lower end of the exhaust valve is arranged so that its extreme extended end seats against the angular exhaust valve seat. This flared head portion of the exhaust valve includes 5 an annular bead or hump 23 for gas deflecting purposes.

The flare described in detail in cross section is formed on three radii; one forming the bead 23 which is intermediate, another forming the 10 curved portion 24 connecting the bead to the stem or slidably mounted portion of the valve, and the third forming a curved and flared seating end 25 of the valve. As will be apparent from Figure 2, when the valve is open the hot gases strike this 15 last mentioned curved portion 25, the outer surface of which is concave and the discharge gases are directed in a circular path off the bead as a result of contact with this concave annular surface.

20 The bead is sufficiently extended to cause the hot gas flow to clear the extended end of the guideway 22, it being clear also that the hot gases cannot be directed against the exposed guide stem portion of the valve when the valve is in open 25 position. This is important since at this time it is necessary that a certain portion of the finished guide surface be exposed. Thus it is provided that the major portion of the heat flow, particularly in its primary stages, is directed 30 away from the guideway and exposed portion of the valve stem. It will be apparent that this is highly advantageous in that the gases and flame passing through the exhaust port cannot burn or damage the guide and valve parts.

35 Having described my invention, I claim:

1. In an internal combustion engine, an engine body having a cylinder, said body having a valve structure including an exhaust passageway extending axially from said cylinder, the exhaust 40 valve seat being arranged concentrically of the exhaust passageway, an exhaust valve of sleeve form having a flared head end engageable with said seat, internal and external guides for said exhaust valve of sleeve form, the external guide 45 extending across the exhaust passageway adjacent to the exhaust valve seat, said exhaust valve head including an outwardly formed annular bead in the flared portion thereof, and the outer surface of the valve head between the bead and the seating portion thereof being curved on a radius 50 which directs the gases through the exhaust passageway entirely clear of the valve guide and the sleeve valve beyond the flared head.

2. In an internal combustion engine, an engine body having a cylinder, said body having a valve structure including an exhaust passageway extending axially from said cylinder, the exhaust valve seat being arranged concentrically of the exhaust passageway, an exhaust valve of sleeve form having a flared head end disposed in the upper part of the cylinder for engagement with 55 said seat, an external guide for said exhaust valve of sleeve form extending across the exhaust passageway substantially to the exhaust 60 valve seat, said exhaust valve having its head formed for directing the gases through the exhaust passageway entirely clear of the valve guide and the sleeve valve beyond the flared head.

3. In an internal combustion engine, an engine 70 body having a cylinder, said body having a valve structure including an exhaust passageway extending axially and laterally from said cylinder, the exhaust valve seat being arranged concentrically above the cylinder bore, an exhaust valve 75 of sleeve form having a flared head end disposed

in the exhaust outlet and upper part of the cylinder for engagement with said seat, internal and external guides for said exhaust valve, said external guide of sleeve form and extending partially across the exhaust passageway, said exhaust valve head including an annularly formed outwardly disposed hump in the flared portion thereof, and the outer surface of the valve head between the hump and the seating portion thereof being concave whereby the hot gases are directed through the exhaust passageway away from the external valve guide and the sleeve valve beyond the flared head. 5 10 15 20

4. In an internal combustion engine, including a body having a cylinder and a valve structure 15 including an exhaust passageway therein and an exhaust valve seat in said passageway; an exhaust valve of sleeve form extended across said exhaust passageway and having a head adapted to engage said seat, a guide surrounding the body of 20 said valve and extended partially across said exhaust passageway, said valve head formed for deflecting the hot exhaust gases away from the portion of the body of said valve and the portion of said guide disposed in said passageway. 25

5. In an internal combustion engine including the engine body having a cylinder and a valve structure including an exhaust passageway; an exhaust valve disposed across the exhaust passageway and adapted to seat at the upper end of 30 the cylinder, a guide surrounding the stem of said valve, said exhaust valve being of sleeve construction and including a flared head end, said flared end formed on three radii presenting annular outer surfaces concave in cross section and 35 an intermediate outer annular surface convex in cross section, the intermediate surface being extended sufficiently in conjunction with the end of the head for deflecting the hot gases passing between the end of the head and the seat, in an 40 arc and entirely away from the stem of the valve and the guide where they extend across the exhaust passageway.

6. In an internal combustion engine, an engine body including a cylinder block and head, a 45 piston in the cylinder of the block, said body having an inlet passageway leading to the cylinder and having an exhaust outlet leading from said cylinder, an exhaust valve guide mounted in said cylinder head, concentrically disposed inlet 50 and exhaust valves mounted in said guide for controlling the respective passageways, said exhaust valve being slidably mounted in said guide and having a head for closing said outlet, the outer surface of said exhaust valve head having 55 an outwardly extending heel integrally formed therewith and positioned adjacent said exhaust outlet, the inner surface of one end of said guide being inclined outwardly and having the same contour as the adjacent outer surface of said heel 60 whereby a space is provided between said exhaust valve and said end of said guide when said exhaust valve is in closed position, said heel of said exhaust valve head being received in said space when said exhaust valve is in open position and said heel being adapted to deflect the burned fuel gases which escape from said cylinder through said outlet and shield said exhaust valve guide therefrom. 65

7. In an internal combustion engine, an engine 70 body including a cylinder block and head, a piston in the cylinder of the block, said body having an inlet passageway leading to the cylinder and having an exhaust outlet leading from said cylinder, a valve guide mounted in said cyl- 75

- inder head, inlet and exhaust valves mounted in said guide for controlling the respective passageways, said exhaust valve being slidably mounted in said guide and having a head for closing said outlet, the outer surface of said exhaust valve head having an outwardly extending heel integrally formed therewith and positioned adjacent said exhaust outlet, said heel being adapted to deflect the burned fuel gases which escape from said cylinder through said outlet and shield said exhaust valve guide therefrom.
8. In an internal combustion engine, a body having a cylinder therein, an engine head including an intake passageway and an outlet passageway, said passageways including valve seats, valves controlling the respective passageways, said exhaust valve having a stem of tubular form and including a flared head the outer end of which is adapted to engage the valve seat of the exhaust passageway, said valve head including an outwardly disposed circumferential bead formed integrally therewith between the seating portion thereof and the tubular stem thereof for deflecting the burned fuel gases away from the valve stem.
9. In an internal combustion engine, a body having a cylinder therein, an engine head incorporating an inlet passageway and an outlet passageway, said passageways including valve
- seats respectively, an exhaust valve mounted in said head and disposed across said outlet passageway, said valve comprising a tubular stem and a tubular head, an intake valve disposed concentrically within said exhaust valve, said valves cooperating with their respective seats, said inlet passageway extended through said exhaust valve and into said cylinder, and the tubular head of said exhaust valve flared outwardly from the stem thereof and including means formed integrally with said flared head for deflecting the hot exhaust gases away from the valve stem.
10. In an internal combustion engine, a body including a cylinder and an exhaust passageway therefrom, said passageway including an exhaust valve seat, an exhaust valve extended across said exhaust passageway, said exhaust valve including a stem of tubular form and an outwardly flared head the outer margin of which is adapted to engage said seat, said flared valve head including a circumferential hump formed therein between the seating head and the tubular valve stem, said hump disposed beyond the outer surface of the valve stem and adapted to deflect the hot exhaust gases completely away from the valve stem.
